UNITED STATES PATENT OFFICE

120,174

DESIGN FOR A COMBINED BROOCH AND LOCKET

Victor Silson, New York, N. Y.

Application February 23, 1940, Serial No. 90,441

Term of patent 3½ years

To all whom it may concern:

Be it known that I, Victor Silson, a citizen of the United States of America, residing in city of New York, county of New York, and State of New York, have invented a new, original, and ornamental Design for a Combined Brooch and Locket, of which the following is a specification, reference being had to the accompanying drawing, forming part thereof.

Fig. 1 is a plan view of a combined brooch and locket showing my new design.

Fig. 2 is an edge view thereof.

I claim:

The ornamental design for a combined brooch and locket, substantially as shown.

VICTOR SILSON.
